Term of patent 14 years

Int. Cl. D6—11

U.S. CL. D12—203

FIG. 1 is a top plan view of an automobile floor mat embodying our new design.

FIG. 2 is a fragmentary vertical sectional view on an enlarged scale taken along line 2—2 of FIG. 1.

FIG. 3 is a fragmentary vertical sectional view on an enlarged scale taken along line 3—3 of FIG. 1.

FIG. 4 is a fragmentary vertical sectional view on an enlarged scale taken along line 4—4 of FIG. 1.

FIG. 5 is a fragmentary vertical sectional view on an enlarged scale taken along line 5—5 of FIG. 1.

FIG. 6 is a fragmentary vertical sectional view on an enlarged scale taken along line 6—6 of FIG. 1.

FIG. 7 is a fragmentary portion of the top plan view on a greatly enlarged scale of the area underlying line 7—7 of FIG. 3; and

FIG. 8 is a fragmentary vertical sectional view on an even greater enlarged scale taken along line 8—8 of FIG. 7.

The patterns which are partially shown for ease of illustration are understood to be continuous throughout the areas indicated. The undisclosed bottom is substantially flat and unornamented.

We claim:

The ornamental design for an automobile floor mat, as shown and described.
